UNITED STATES PATENT OFFICE.

DANIEL S. COOKE, OF PROVIDENCE, RHODE ISLAND.

FAN.

SPECIFICATION forming part of Letters Patent No. 275,804, dated April 17, 1883.

Application filed August 12, 1882. (No model.)

To all whom it may concern:

Be it known that I, DANIEL S. COOKE, of the city and county of Providence, and State of Rhode Island, have invented a new and useful Improvement in Fans; and I do hereby declare that the following specification, taken in connection with the accompanying drawings, forming a part of the same, is a full, clear, and exact description thereof.

My invention consists in a fan having a non-folding blade, which is provided with a pocket or receptacle adapted to be closed and temporarily to hold a sachet, cards, tickets, or other small articles used or carried by ladies, as will hereinafter appear.

Referring to the drawings, Figures 1 and 2 represent respectively front and side views of a fan embodying my invention. Fig. 3 shows a front view of a fan with the flap of the pocket or receptacle raised to give access to the interior.

The fan-blade A and pocket or receptacle B may be made in any preferred shape and of any proper material, and the pocket B be secured to the blade or body of the fan by stitching, rivets, cement, or in any preferred manner. Preferably the pocket is provided with a flap, b, which may be fastened by a clasp, as shown in Fig. 1, or by a tongue and loop, as shown in Fig. 2, to retain the articles within

the pocket, although the receptacle may have a self-closing elastic mouth, or a mouth provided with gathering-strings, if the material of the pocket be sufficiently flexible. One or more pockets, B, may be arranged on one or both sides of the fan-blade, as desired.

My improved fan not only serves its usual and proper purpose as a fan, but, in addition, provides a convenient receptacle for a sachet, allowing the air to be perfumed as the fan is moved, or for cards, car or theater tickets, or other articles. My improved fan therefore is doubly useful, and it may be made highly ornamental.

I claim—

1. As an improved article of manufacture, a fan having a non-folding blade, to which is secured a pocket or receptacle the interior of which is accessible, substantially as and for the purposes specified.

2. As an improved article of manufacture, a fan having a non-folding blade, to which is secured a pocket or receptacle, B, having a flap, b, and means for securing the flap in a closed position, substantially as described and shown.
